UNITED STATES PATENT OFFICE.

THOMAS HENDRICK, OF BOWLING GREEN, KENTUCKY.

FEED-RACK.

SPECIFICATION forming part of Letters Patent No. 247,346, dated September 20, 1881.

Application filed June 18, 1881. (No model.)

To all whom it may concern:

Be it known that I, THOMAS HENDRICK, a citizen of the United States, residing at Bowling Green, in the county of Warren and State of Kentucky, have invented a new and valuable Improvement in Feed-Racks; and I do hereby declare that the following is a full, clear, and exact description of the construction and operation of the same, reference being had to the annexed drawing, making a part of this specification, and to the letters and figures of reference marked thereon.

The figure of the drawing is a representation of a perspective view of my invention.

This invention has relation to feeding-racks; and it consists in the construction and novel arrangement of parts, as hereinafter shown and described.

In the accompanying drawing, the letter A designates the ground bars or runners on which the rack is supported. In these runners, near their ends, are cut the dovetail notches *a*, whereby the runners are connected to the dovetail ends *b* of the transverse bars *B*, being set up against the shoulders *c* of said transverse bars so as to insure firm bearing and parallel position. The transverse bars *B* are provided with draft-staples *d* or eyebolts for the attachment of a whiffletree.

C C designate the cross-bars which form the ends of the rack-frame. The lower ends of these bars are secured to the transverse bars *B*, and above said bars, at about the proper height for feeding, said bars are halved into each other, as shown at *e*. Below this crossing the bars C C therefore form the supporting-legs of the rack, and above it they extend upward, forming the end bars of the rack, said supporting-legs and end bars being inclined laterally, as shown in the drawing.

D represents the longitudinal center bar, extending from end to end of the rack between the crossings *e*, and to this center bar the cross-bars C C are firmly secured. Perforations are made in the center bar, on each side of its upper portion, to receive the lower ends

of the rack-sticks *E*, the upper ends of which are inserted in perforations made in the longitudinal cap or framing bars *F*, which are notched at their ends to receive the notched ends of the transverse cap-bars *G*. Cross rack-sticks *H* are arranged at the ends of the rack, their upper and lower ends being inserted in perforations made respectively in the transverse cap-bars *G*, and in the cross bars *C*.

K K indicate the feeding-boxes, which extend on each side the full length of the rack. These feeding-boxes are made with upwardly and outwardly inclined sides *g*, whereof the angle of inclination is about equal to that of the cross-bars C C, which form bearings for the ends of said feeding-boxes, as indicated at *h*, these bearings being below the crossings *e* of said bars. In order to insure a firm engagement, the bearings *h* are provided with studs or projections *k*, which are designed to engage perforations *l* in the sides of the boxes. Fastening-hooks *m* are pivoted to the cross-bars, and engage the staples *n* on the ends of the boxes centrally, so the latter are detachable.

L L indicate attachment-links, which are connected to the ends of the transverse bars *B*, and serve as means for securing the rack in stationary position, suitable stakes being driven through said links into the ground.

Having described this invention, what I claim, and desire to secure by Letters Patent, is—

The feed-boxes K K, having the inclined walls *g*, perforated at *l*, and the loops *n*, in combination with the inclined frames having the bearing-studs *k* and hooks *m*, whereby the boxes are held in place and are detachable from the frame, as set forth.

In testimony that I claim the above I have hereunto subscribed my name in the presence of two witnesses.

THOMAS HENDRICK.
